UNITED STATES PATENT OFFICE.

WILLIAM McILVRID, OF JERSEY CITY, NEW JERSEY, ASSIGNOR TO THE COCKBURN BARROW AND MACHINE COMPANY, OF JERSEY CITY, NEW JERSEY, A CORPORATION OF NEW JERSEY.

AIR-LOCK FOR CAISONS.

No. 810,298.

Specification of Letters Patent.

Patented Jan. 16, 1906.

Application filed June 22, 1905. Serial No. 266,488.

To all whom it may concern:

Be it known that I, WILLIAM McILVRID, of Jersey City, in the county of Hudson and State of New Jersey, have invented certain new and useful Improvements in Air-Locks for Caissons; and I do hereby declare the following to be a full, clear, and exact description of the invention, such as will enable others skilled in the art to which it appertains to make and use the same.

The object of this invention is to provide an improved air-lock for caissons, having special reference to the means for opening and closing the lock to permit of removing and replacing the bucket.

As heretofore designed air-locks have usually been provided with doors at their upper and lower ends. These have either been of the two-part downwardly-swinging type, or means have been employed for sliding the doors horizontally, or one portion of the cylinder end has been stationary and the other movable. In the use of all of these forms when manually operated it is necessary for the attendant to operate the doors from an inconvenient position at the top or upper end of the lock. When the bushing through which the cable passes is formed by the door or doors, whether swinging or sliding, there is a pronounced tendency to leakage or the closing of the door or doors causes a binding upon the rope and consequent difficulty in raising or lowering the bucket. When downwardly-swinging doors are employed, the bucket must necessarily be of limited capacity, since its size must allow the doors to swing down above it while it is within the cylinder. By my invention these difficulties are overcome.

Broadly stated, I provide a door or doors extending longitudinally of the lock, at the side thereof, which may terminate within or be coextensive with the height of the cylinder.

The invention will be hereinafter fully set forth, and particularly pointed out in the claims.

In the accompanying drawings, Figure 1 is a side elevation, partly in section. Fig. 2 is an end view. Fig. 3 is a slight modification. Fig. 4 is a detail.

Referring to the drawings, 1 designates the casing or cylinder of an air-lock, and 2

a single swinging door extending entirely across the lower end, such door being suitably pivoted and counterbalanced. The casing at its upper end is partially closed by a fixed part 3, which comprises a plate 4, the exterior thereof presenting in plan view a U shape, the edge of such plate being secured to an angle-iron 5, riveted to the casing. The central curved portion of the part 3 at its edge is recessed to accommodate a sleeve or bushing 6 on the hoisting-cable. The longitudinal side members of the fixed part 3 are beveled on their under sides 7 from their outer ends inwardly toward the axial center of the lock. (See Fig. 4.)

8 is the door for covering the inlet and outlet opening extending the full length of the lock and covering that portion of the top over which the stationary part 3 does not extend. As shown, this door is suitably pivoted at 9 to the casing and is formed at its upper end with a ledge 10, having its free edge curved to correspond to the curved edge of part 3. The ledge 10 works beneath the longitudinal sides of the part 3, so that in closing the door the ledge moves in tight frictional contact with the beveled faces 7 and its vertex binds against the bushing 6. A perfectly tight joint is thus provided, and to further preclude the possibility of leakage a rubber gasket 12 is attached to the edges of the door.

At 13 I have indicated appropriate means for locking the door. Any preferred means may be employed, however, such as pistons operated by air-pressure, as well known in the art.

In practice the bucket may be nearly the full length of the lock, since no space is sacrificed on account of the door. Once the bucket is raised into the lock and the lower door 2 is closed and pressure relieved from the inclosure, as customary, the door is swung open, carrying with it the ledge 10, which uncovers nearly one-half of the top. Thereupon the bucket may be swung laterally and outwardly or upwardly, the bushing 6 being carried on the cable. It will be seen that a bucket of maximum capacity may be employed and that as soon as it is returned to the lock and the bushing placed in position the closing of the door will not only cover the side opening of the lock, but will

also close the top thereof, the fit of the ledge beneath the stationary part 3 preventing any possible leakage.

The invention is capable of embodiment in various forms. For instance, as shown in Fig. 3, two doors 14 may be employed to cover fully one-half the casing, so as to allow for an increased opening in the casing. These doors are mounted to slide circumferentially of the casing on a rail 15, at the top thereof. In this form the casing is truly circular, so that the doors of corresponding formation may be moved axially thereof in opposite directions. The doors are provided at their meeting edges with locking devices 16. In practice the two doors are moved apart until they telescope one half of the casing, leaving the other half entirely open. This is advantageous where an opening of maximum capacity is desired.

It is apparent that in the preferred form of embodiment illustrated in Figs. 1 and 2 the single door may constitute one-half of the casing.

From what has been said it will be seen that my invention provides means whereby the bucket may be of size nearly equal to that of the lock-casing, as there are no inwardly-moving parts for which space must be allowed. The bushing is not interfered with or subjected to wear and will retain the cable securely when the lock is closed.

It will be understood that suitable means is to be employed for equalizing the air-pressure in the lock-casing; but as this may be done in any preferred way I have not made specific mention thereof.

I claim as my invention—

1. In an air-lock for caissons, a casing having a stationary top portion extending partially over the upper end thereof, said casing having an opening in its side extending lengthwise thereof to permit of removing and replacing the bucket, and means for simultaneously closing said opening and that part of the top of the casing not covered by said stationary portion.

2. In an air-lock for caissons, a casing having a lower door, a stationary top portion extending partially over the upper end of said casing, a bushing for the hoisting-cable designed to be accommodated by the edge of said top portion in line with the center of the opening closed by said lower door, said casing having an opening in its side extending

lengthwise thereof, and means for simultaneously closing said opening and that part of the top of the casing not covered by said stationary portion.

3. In an air-lock for caissons, a casing having an opening at its side extending lengthwise thereof, a door for closing said opening, and means for holding a hoisting-cable in fixed relation to said casing when said door is closed and for releasing the same when said door is opened to permit the bucket and cable to be removed through said opening.

4. In an air-lock for caissons, a casing, a fixed closure partially covering the upper end of said casing, said casing having an opening extending lengthwise thereof at its side, and a door for said opening having a closure at its upper end for coöoperating with the fixed closure at the upper end of the casing.

5. In an air-lock for caissons, a casing having a stationary top portion extending partially over the upper end thereof, said top having its free edge beveled, said casing having an opening at its side, and a door for said opening having a ledge at its upper end for coöoperating with the stationary top portion of said casing to form a complete closure for the upper end thereof, the edge of said ledge being designed to contact with the beveled edge of said top.

6. In an air-lock for caissons, the combination with the casing having an opening in its lower end, means for closing said opening, a stationary top portion extending partially over the upper end of said casing, a bushing removably accommodated by said top in line with the center of said lower opening, said top having portions of its inner face beveled, said casing being open throughout its side and at the part of its upper end not covered by said top, of a door pivotally mounted upon said casing and forming a closure for said side and provided with locking devices, said door having a ledge forming a closure for the upper end of the casing and designed to be accommodated beneath the beveled portions of said top.

In testimony whereof I have signed this specification in the presence of two subscribing witnesses.

WILLIAM McILVRID.
